UNITED STATES PATENT OFFICE

ROSCOE E. MAJOR, OF CHICAGO, ILLINOIS, ASSIGNOR TO MAJOR EQUIPMENT CO., INC.,
A CORPORATION OF ILLINOIS

LENS-HOLDING LOCK FOR REFLECTORS

Application filed February 6, 1930. Serial No. 426,298.

This invention relates to improved means for retaining the glass lenses of ceiling flood-lights in position on the frame or reflector part of the lamp holder.

5 The purpose of the invention is to provide a safe and easily manipulated clamp for the lens. Many appliances now in use for supporting the lenses of floodlights are not safe, because of variability of adjustment resulting in the uncertainty as to being in the fully on or off clamping positions, and lack of capacity for easy manipulation. It is therefore an object of this invention to provide lens latching means or clips which, by 10 15 20 25

the pressure of a finger in one direction, may be moved out of engagement with the lens ring, retained in such position, and by a mere touch will spring back into the full latching position.

20 The purposes of the invention are accomplished by the latch construction illustrated in the accompanying drawings, wherein:

Figure 1 is a bottom plan view of the ceiling lamp holder, including the lens and latches shown in retaining position.

Figure 2 is a sectional view taken on the line 2—2 of Figure 1.

Fig. 3 is a fragmentary bottom plan view, showing one of the latches retained disengaged from the lens ring.

Fig. 4 is a side view of one of the latches showing the lens and associate parts of the lamp holder in section as taken on the line 4—4 of Fig. 1.

35 Fig. 5 is a side view of the latch in its disengaging position, with a fragment of the reflector and lamp holder in section, and with the lens removed.

Fig. 6 is a perspective view of the latch as it would appear when turned upside down.

Fig. 7 is a perspective detail of the movable clip part of the latch as it appears in Figure 6.

45 Fig. 8 is a longitudinal sectional view of the latch.

Fig. 9 is a transverse sectional view of the latch taken on the line 9—9 of Fig. 8.

Fig. 10 is another longitudinal section for 50 the purpose of illustrating the position of

the lens clip part of the latch as it appears when retained in its disengaging position.

In order to provide a safe construction for the purpose of retaining ceiling floodlight lenses in position on lamp housings, a latch is provided which, when slid to disengaging position, is automatically retained in such position, and will, by a mere touch of a finger, spring back to latching position.

This easy operation causing the latches to spring from the disengaging position to the engaging position without any other manipulation than a mere touch, is of particular utility under the circumstances of difficult accessibility generally the case in regard to ceiling floodlights. It is convenient to one changing a lamp bulb or cleaning the light, since the lens may be held in position by one hand, while nothing but mere touches from the other hand are required to fully set the retaining clips. The lenses are sometimes rather heavy and large, and it is decidedly inconvenient to manipulate screws or to hold latches in releasing position while the lens is placed in its proper position.

Each latch comprises the stampings 1, 2, 3 and a coil spring 4. The stampings 1 and 3 are secured together and constitute a fixed rigid frame structure within which is slidably mounted the lens clip, part 2. Fig. 9 shows how the parts 1 and 3 are bent to form a guideway for the slide or clip 2. The spring 4 bears against the upwardly extending lug 5, which is punched and pressed outwardly from part 2, leaving the recess 6 in the latter.

The part 3 of the structure is a spring barrel and is clipped rigidly to the member 2 by bent lugs 7, which are struck from part 3 and passed through slots in part 1.

The spring barrel 3 is provided with an integral end portion 8, against which one end of the spring bears, and the edge 9 of the end part of the spring barrel serves as a guide and fulcrum for latch slide 2. The slide 2 is also recessed at 10 at each side for receiving guide flanges 11, bent inwardly from part 1. The flanges 11 are limited in length according to the desired stroke of

the clip 2, and are cut away at their ends, as indicated at 12, Fig. 6.

When the slide part 2 of the latch is shifted to its disengaging position, by pressure of the finger on grip 14, the spring 4 causes the clip 2 to assume the angular position indicated in Fig. 10. The clip is rendered free to assume this position because of the recesses 12, and because of the action of spring 4, which forms a couple with the fulcrum 9. The clip is retained in disengaged position because it bears against the end flanges 11 at recesses 12. In order to cause the clip to move into the lens retaining position, it is merely necessary to press against its end 13, and thereby disengage it from the ends of flanges 11, and permit it to move to latching position under the action of spring 4.

I claim:

1. Lens latching means comprising a fixed frame of two parts bent and secured together to form a longitudinally extending guideway for a slidable latching clip, a latching clip movably mounted in the guideway and provided with a lug projecting to one side of the guideway, a spring bearing between said lug and a portion of said frame structure at one side of said guideway, said frame structure being formed to provide a fulcrum for the clip around which the clip may move perpendicularly to its longitudinal movement, said spring and fulcrum forming a couple, and means preventing the perpendicular movement of the clip except at one point of its longitudinal stroke.

2. Lens latching means comprising a two-part frame structure, one of said parts being bent to provide attaching flanges and the other part being bent to form a spring barrel, the two parts of said frame structure also being formed to provide a guideway, a latching clip slidably mounted in said guideway, a spring in the spring barrel bearing against one end of the barrel and said sliding clip, guide flanges on said frame structure, and recesses in the clip for engaging said guide flanges, said guide flanges being cut away at one end to allow the clip to move perpendicularly of its normal longitudinal stroke and be retained in such position by bearing against the ends of said guide flanges under the action of said spring.

3. Lens latching means comprising a fixed frame structure arranged to form a guideway for a latch clip, a latch clip slidably mounted in said guideway for longitudinal motion, a spring between said frame structure and latch clip for urging the clip to move into its latching position, said spring being positioned to rock the latch clip perpendicularly to its longitudinal movement when the latch clip is in the unlatching position, and means on the frame for retain-

ing the clip in its unlatching position when the latch is shifted perpendicularly to its longitudinal movement.

Signed at Chicago this third day of Feb., 1930.
